UNITED STATES PATENT OFFICE

FRANCISCO IGNACIO DE CHRISTO, DECEASED, LATE OF HORTA, FAYAL, AZORES ISLANDS, PORTUGAL, BY FLORINDA DE CHRISTO RODRIGUES, ADMINISTRATRIX, OF OAKLAND, CALIFORNIA

FLYING MACHINE

Application filed February 16, 1928. Serial No. 254,867.

This invention relates to improvements in flying machines, and consists more particularly in the disposition of the wings, and of the tail containing hydrogen, and in the application of mechanism which in connection with a motor will be subject to guidance and control in the air.

With these ends in view the invention consists in the certain features of construction and combinations of parts as will be hereinafter fully described and pointed out in the claims. In the accompanying drawings,

Figure 1 is a vertical longitudinal view on lines 1—2 of Figure 2.

Figure 2 is a horizontal plan view on lines 3—4 of Figure 1.

Figure 3 is a transverse longitudinal section on lines 5—6 of Figure 2.

Figure 4 is a vertical longitudinal section of the head.

Figure 5 is a horizontal section of the same.

Figure 6 is an end view of the tail.

The body 1 of the machine is preferably composed of light metal and is divided into compartments or cabins which are capable of accommodating several passengers. An electric motor 2 is fixed centrally in the body of the machine, however it is understood that any style of motor may be employed.

The wings 3 being formed in simulation of the wings of a bird are pivotally secured to the body 1 on each side thereof as shown at 4. The wings are provided with reinforcing rods 5 and have struts 6 extending longitudinally thereof. The rods 5 are connected by means of a universal joint 7 to the eccentric shaft 8 of the motor. The wings are further provided with the vertical bracing ribs 9 which are connected with a silk bandruche or other impervious covering for the purpose of retaining the hydrogen that is introduced into the wings by the way of an orifice not shown, the same being disposed beneath the wings.

10 is a propeller shaft journalled in the brackets 11 and is connected with the drive shaft 12 of the motor by means of a chain 50 of gears 13, through which rotation is com-

municated to the propeller 14 on the end of shaft 12.

The tail 15 of the machine is a metallic hollow structure covered with silk or bandruche which is supplied with hydrogen. This tail is attached to the back of body 1 by means of a suitable universal joint. Tail 15 may be oscillated to right and left by means of the cables 16 which are also attached to the head 17 of the machine. These cables extend downwardly to guides 18 and are carried forwardly crossing each other intermediate the tail and the head with their ends attached to the diametrically opposite sides of the head.

The head 17, which functions as a rudder, is preferably formed of light metallic plates 19 and is in semblance of the head of a bird having therewithin a pilot's compartment. The head portion of the structure is pivotally related to the forward end of the body portion thereof, being journaled on rod 19 which is secured at its lower end to the floor 21.

The movement of the head 17 from right to left in a horizontal plane in synchrony with the tail 15 for steering the machine is accomplished by steering wheel 22 secured to the steering post 23, which post has secured thereto, at its lower end, pinion 24 meshing with segment 25 affixed to the floor 21. From the mechanism just described, it will be readily seen that if the steering wheel 22 be rotated in either direction by a pilot positioned therebehind, that the turn table 28 will move in unison with and in the same direction of rotation as the head 17, thereby always keeping the pilot in alignment with lookouts 29 in order that he may at all times observe the conditions ahead of the machine. The steering post 23 passes through the arm 26 which is secured to the staff 27. It will be observed (see Fig. 4) that the turn table 28 necessarily moves with the head 17 independently of the body 1 in the pivotal movement of the head in a horizontal plane from right to left.

Upon movement of the head, to either right or left, there will be a corresponding movement of the tail, due to the cables 16. The cables 16 are attached to both sides of the

tail and pass thru guides 18, which are disposed below the horizontal plane in which the tail lies, so that upon a difference in tension in the cables 16, the tail will have a tendency to rotate.

5 The opposite ends of the cables 16 are suitably attached to the head. When the head is pointing directly forward, there is neutral tension between the cables and the tail 10 is perfectly horizontal. Upon movement of the head to the right, for example, a difference in tension is set up and there will be a corresponding partial revolution of the tail in a clockwise direction. Similarly, upon 15 movement of the head to the left, the tail revolves in the opposite direction. Figure 6 illustrates the various positions of the tail due to the action of the head and cables 16.

It will be understood that the head is in 20 effect a vertical rudder and that the simultaneous action of the tail with that of the head, greatly facilitates the turning of the machine.

25 The operation of the machine is as follows: Motion is communicated to the wings by means of the motor, and rotation of the propeller is produced at the same time.

It will be noted from Figure 3 that the bottoms of the outer portions of the wings 30 are generally concave and the tops generally convex. On the downward stroke, therefore, there will be a concentration of pressure built up on the under, concave portion of the wing and a lack of pressure approaching a vacuum 35 on the top of the wing. On the upward stroke, the pressure on both sides of the wing will be more nearly balanced.

Movement of the wings hence causes the 40 machine to rise, since the wings encounter a greater resistance on the downward than on the upward stroke. It must be understood that the machine is practically buoyant due to the presence of the hydrogen in the wings and tail and only a slight force is required to 45 get it aloft.

45 The propeller imparts a forward motion to the machine.

From the foregoing description it will be 50 readily seen that when the head 17 is turned to the right or left by the operation of the steering wheel 22 that the tail 15 will be caused to pivot in the same direction while simultaneously pivoting on its longitudinal axis throwing the right hand or left hand 55 edge, according to the direction in which the rudder is turned about its vertical axis, downwardly by reason of the cables 16 passing downwardly through guides 18 below the horizontal plane of the tail and are then 60 crossed having their forward ends attached to diametrically opposite sides of the head 17, which results in the provision of a rudder at both the forward and rear ends of the machine which are actuated simultaneously.

65 Having fully described the invention, what

is claimed and desired to secure by Letters Patent is:

1. A flying machine comprising a body portion, a pilot's compartment constituting a rudder and capable of pivotal movement with relation to the forward end of the body portion, a floor in said compartment, a toothed segment affixed to the floor, a steering post, a pinion meshing with the segment carried by the steering post and a wheel for imparting rotary movement to the pinion. 70

2. A flying machine comprising a body portion, a pilot's compartment constituting a rudder and pivotally related to the front end of the body portion, a rudder pivotally related to the rear end of the body portion and steering instrumentalities for imparting pivotal movement to the pilot's compartment and the rudder in a horizontal plane about vertical axes while simultaneously imparting pivotal movement to the rudder about its horizontal longitudinal axis. 80
